UNITED STATES PATENT OFFICE.

WILLIAM R. WILSON, OF COLUMBUS, OHIO.

DESIGN FOR A CARRIAGE-STEP.

SPECIFICATION forming part of Design No. 21,780, dated August 16, 1892.

Application filed June 4, 1892. Serial No. 435,581. Term of patent 3½ years.

To all whom it may concern:

Be it known that I, WILLIAM R. WILSON, a citizen of the United States, residing at Columbus, in the county of Franklin and State of Ohio, have invented and produced a new and original Design for Carriage-Steps, of which the following is a specification, reference being had to the accompanying drawing, forming a part thereof.

10 The figure shown in the drawing represents in perspective my newly-designed step, this view being deemed necessary to fully illustrate the same.

15 The leading features of my design consist in the arms *b c*, provided with a hexagonal pad, the upper surface of the latter presenting parallel corrugations.

Referring to the drawing, *a* represents the flattened pad, the outline of which forms a hexagonal body, as shown. The upper surface of this pad is provided with parallel corrugations or grooves. *b c* represent, respectively, arms which project from said pad, said arms being so formed that when viewed in cross-section a hexagonal outline is produced. 20 25

What I claim, and desire to secure by Letters Patent, is—

The design for a carriage-step, as herein shown and described.

WILLIAM R. WILSON.

In presence of—

C. C. SHEPHERD,
THOS. S. GATES.
